UNITED STATES PATENT OFFICE

FRANK A. LINDGREN, OF WESTERN SPRINGS, ILLINOIS, ASSIGNOR TO GOODMAN MANUFACTURING COMPANY, OF CHICAGO, ILLINOIS, A CORPORATION OF ILLINOIS

CUTTING AND LOADING MACHINE

Application filed August 11, 1928, Serial No. 298,920. Renewed July 29, 1931.

The invention herein described is especially adapted to machines of the overcutting or slabbing type, which are more particularly used in cutting slate or dirt bands in the coal face. The plate mixes with the coal and causes great trouble and expense in that it has to be removed by hand either at the mine face or outside at the tipple. My invention eliminates this hand operation and provides a means to gather these cuttings and convey them to a point remote from the face of the coal.

My invention may best be understood with reference to the accompanying drawings, wherein:

Figure 1 is a top plan view of the device embodied in my invention with the cutting element at right angles to the longitudinal axis of the truck and with parts broken away to more clearly show my invention;

Figure 2 is a front end view of the device shown in Figure 1;

Figure 3 is an enlarged fragmentary view of the cuttings deflection means used in my invention;

Figure 4 is a sectional view taken on line 4-4 of Figure 3; and

Figure 5 is a partial enlarged fragmentary sectional view looking from the front end of the machine showing certain details of construction of a portion of the device embodying my invention.

Referring now more particularly to the drawings, it may be seen that the device embodying my invention is applied to a mining machine 10 of the well known overcutting or slabbing type, and comprises means for gathering and conveying the cuttings away from said machine and depositing said cuttings on the mine floor remote from the face in the gob or in any suitable receiving device, such as I have described in a prior application, Serial Number 243,846, filed December 31, 1927.

The mining machine 10 comprises a truck portion 11 supported on axles and wheels in an ordinary manner. An auxiliary supporting frame 14 is mounted for rotation near the forward portion of the truck 11 and has suitable means thereon for supporting a cut-

ting element 16. Herein said supporting means comprises a plurality of supporting arms 17, 17, having racks 18, 18, thereon. Pinions 19, 19, on the cutting element 16 mesh with the racks 18. The pinions 19, 19 are connectible with a motor 20 carried by the cutting element 16 through any suitable gearing means (which need not be described here since it is no part of my invention), for vertically moving said cutting element in the racks 18 to provide a means for cutting at a plurality of vertical heights. The supporting frame 14 is also rotated by a suitable gear reduction means from a motor 21 on the rearward portion of the truck portion 11 in the well known manner of machines of this type.

Therefore, when the frame 14 is rotated, the cutting element 16 is moved in an arc which in turn provides a means for sumping a cutter bar 22 having a cutter chain 23 thereon into the coal for cutting said coal.

Referring now more particularly to the novel features of my invention, cuttings gathering and conveying means are provided to gather the cuttings discharged from the cutter chain 23 while said cutter chain is cutting a kerf along a mine wall, and discharge said cuttings beyond the machine into the gob or into any suitable receiving device. To accomplish this a conveying element 25 is detachably supported on the side of the truck portion 11 adjacent the face of the coal when the mining machine is moving parallel to the face of the coal to cut a kerf therein, so that said conveying element is directly beneath the cutter bar 22 when the longitudinal axis of said cutter bar is perpendicular to the longitudinal axis of the truck portion 11. The conveying element 25 extends to each side of the cutter bar 22 a sufficient distance to catch all of the cuttings discharged from the cutter chain 23 and discharges said cuttings into a second conveying element 28 at one end of the truck portion 11 and disposed at right angles thereto so as to discharge the cuttings rearwardly of the cutting element 16 when said cutting element is in the position shown in Figure 1. The conveyor element 28 is preferably also supported on the same track which supports the min-

ing machine 10.

ing machine 10 on a trailer truck 29, as shown.

In connection with the conveyor 25, I provide a cuttings deflector or apron 30, which is pivotally connected to the outer edge of the conveyor 25, as will hereinafter more fully appear, and is arranged to abut the face of the coal while the cutting operation is being performed and catch the cuttings discharged from the cutter chain 23 and deflect said cuttings into the conveying element 25.

Since one of the purposes of my machine is to cut out dirt bands on a relatively long face and discharge the dirt cut out at a point 15 away from the face of the coal to prevent said dirt from becoming mixed with the coal, most of the cutting is done with the machine moving parallel to the face of the coal as indicated in Figure 1 and in most instances 20 it is only necessary that the conveying element 25 be held on the side of the truck portion 11 as is shown in Figure 1. However, the conveying element 25 may be detachably connectible to the truck portion 11 so as to 25 be mounted on either side of said truck portion in case it is desired to cut in a direction opposite to that illustrated in Figure 1.

The conveying element 25 may be of any suitable type but herein comprises a belt conveyor 26 of a usual type well known to the art fixed to the truck portion 11 by means of an angle piece 27 fixed to the inner side of said conveyor by any suitable means such as rivets (not shown), and supporting member 31 fixed to the under side of said conveyor and truck portion 11. The angle 27 and supporting member 31 are herein shown as being bolted to the truck portion 11 but may be held to said truck portion by any well known 40 means. A motor 32 is provided to drive the conveyor 26 through drive chains 33 and 34 in a manner well known to the art.

The cuttings deflecting means or apron 30 comprises a plate 35 extending longitudinally 45 of the conveying element 25 having members 36 attached to its lower end pivoted to the conveying element 25 by means of a pivot rod 37. The plate 35 has a plurality of rotatable discs 40, 40, yieldably mounted at its outer 50 or free end adapted to engage the face of the coal in all positions of the plate 35 and to follow uneven surfaces in said coal face to guide the plate 35 along the face of the coal as the cutter bar 22 is cutting a kerf 55 therein.

Each disc 40 is mounted on the under side of the plate 35 when said plate is in such a position that its free end may engage the mine wall on a pin 41 for rotatable movement thereon. A hub 42 of the disc 40 rides in a slot 46 on a supporting member 44. The pin 41 has a head 45 on one end thereof and is 55 slideable in a slot 43 in the plate 35 and the slot 43 in the supporting member 44. A member 47 is threaded on the opposite end

of pin 41. A rod 48 has a head 49 at one of its ends and passes through a hole in a depending portion 50 of the supporting member 44 and its opposite end is threaded in the member 47. A spring 52 surrounds the rod 48 and is interposed between the member 47 and the depending portion 50 of the supporting member 44 to keep the discs 40 in an extreme forward position on the plate 35 and allow said discs to move rearwardly on said plate when obstructions or uneven spots are encountered on the face of the coal, and guide the plate 35 as they travel longitudinally along said coal face.

The trailer truck 29 is supported on axles 56 and track wheels 57, 57, and is adapted to be attached to the forward end of the truck portion 11 so said truck may be moved along with the mining machine as the cutter bar 22 is cutting a kerf in the mine wall. Any suitable means may be used to connect the truck 29 to the truck portion 11. The means herein shown comprise a bar 58 pivoted to the truck portion 11 to swing about a horizontal axis at 59 at one end and pivoted to a clevis 60 on the trailer truck 29 on its opposite end by means of a removable vertically disposed pivotal pin 61. The conveying element 28 is pivoted to the trailer truck 29 near its central portion on a shaft 62 journaled on an axis extending longitudinally of said trailer truck, so said conveying element may be moved in a horizontal position when it is desired to transport the trailer truck 29 about the mine.

The conveying element 28 is herein shown as a belt conveyor 65 of a usual type well known to the art and extends from the forward portion of the conveying element 25 to a point beyond the rearward portion of the cutting element 16 at right angles to the longitudinal axis of the truck portion 11 as shown in Figure 1. The conveyor 65 is driven by an electric motor 66 in a well known manner, as, for instance, by drive chains 67 and 68.

From the above description, it may be seen that my invention comprises a cutting machine of the slabbing or over-cutting type having incorporated therewith a means to catch and discharge the cuttings into the gob beyond the mining machine or load said cuttings into any suitable receptacle. Said invention is especially adapted for use in cutting dirt bands out of coal. The cutter chain 23 on the cutter bar 22 is adapted to cut into the dirt band and expel said dirt from the kerf formed by said cutter chain. The dirt cut out by the cutter chain 23 is caught by the cuttings deflecting means 30 and deflected to the conveying element 25 which deposits these cuttings into the conveying element 28 on the trailer truck 29. The conveying element 28 in turn deposits said cuttings into the gob or any suitable receiving device. It may now be seen that my invention provides a sim-

ple means of separating the dirt from the coal and conveying said dirt away from the face of the coal and that my invention is as adaptable and useful in loading the slack coal cuttings as in separating the dirt from the coal.

5 Although I have herein shown and described one form in which my invention may be embodied, it will be understood that the arrangement and construction of the various

10 parts may be altered or changed without departing from the spirit or scope thereof. Furthermore, I do not wish to be construed as limiting myself to the specific embodiment illustrated, excepting as it may be limited in
15 the appended claims.

I claim as my invention:

1. In an apparatus of the class described, a truck, a cutting element supported on said truck for horizontal pivotal movement, a conveyor at one side of said truck and extending longitudinally therealong, said conveyor being beneath said cutting element, and an apron pivotally connected along the outer edge of said conveyor and having a free end adapted to engage an upright wall in an outwardly inclined position and movable along said wall to guide the cuttings upon said conveyor.

2. In an apparatus of the class described, a truck, a cutting element supported on said truck for horizontal pivotal movement, a conveyor at one side of said truck and extending longitudinally therealong, said conveyor being beneath said cutting element, an auxiliary truck, and a conveyor mounted on said auxiliary truck for receiving the cuttings discharged from said first mentioned conveyor and discharging said cuttings beyond said truck.

3. In an apparatus of the class described, a truck, a cutting element supported on said truck for horizontal pivotal movement, a conveyor at one side of said truck and extending longitudinally therealong, said conveyor being beneath said cutting element, an auxiliary truck, and a conveyor pivotally mounted on an axis extending longitudinally of said auxiliary truck whereby said conveyor may receive the cuttings discharged from said first mentioned conveyor and discharge said cuttings beyond said truck.

4. In an apparatus of the class described, a truck, a cutting element supported on said truck for horizontal pivotal movement, a conveyor at one side of said truck and extending longitudinally therealong, said conveyor being beneath said cutting element, an auxiliary trailer truck detachably connectible with said first mentioned truck, and a conveyor pivotally mounted on an axis extending longitudinally of said trailer truck whereby said conveyor may receive the cuttings discharged from said first mentioned conveyor and discharge said cuttings beyond said truck.

5. In combination with a kerf cutting mining machine, a cutting element including a cutter bar having a cutter chain movable thereabout, a conveyor beneath said cutting element, and a cuttings gathering device pivotally mounted to said conveyor having a plurality of yieldably mounted rotatable discs thereon engageable with a mine wall.

6. In combination with a kerf cutting mining machine, a truck, a cutting element supported on said truck for pivotal movement thereon, a conveyor on said truck beneath said cutting element and extending transversely of said cutting element when said cutting element is perpendicular to the longitudinal axis of said truck, a cuttings gathering device pivotally mounted on said conveyor, and a plurality of rotatable discs yieldably mounted on said cuttings gathering device engageable with a mine wall.

7. In combination with a kerf cutting mining machine, a cutting element including a cutter bar having a cutter chain movable thereabout, a conveyor beneath said cutting element, and an apron pivotally connected along the outer edge of said conveyor and having a free end adapted to engage an upright wall in an outwardly inclined position and movable along said wall to guide the cuttings upon said conveyor.

8. In combination with a kerf cutting mining machine, a cutting element including a cutter bar having a cutter chain movable thereabout, a conveyor beneath said cutting element, and a cuttings gathering device to guide the cuttings upon said conveyor comprising an apron pivotally connected along the outer edge of said conveyor, and having a free end adapted to engage an upright wall in an outwardly inclined position, and movable along said wall, said free end being yieldable so said apron may ride over irregularities on said wall.

9. In combination with a kerf cutting mining machine, a cutting element including a cutter bar having a cutter chain movable thereabout, a conveyor beneath said cutting element and a cuttings gathering device to guide the cuttings upon said conveyor comprising an apron pivotally connected along the outer edge of said conveyor, and having a free end adapted to engage a mine wall in an outwardly inclined position and movable along said wall, said free end comprising a plurality of yieldably mounted rotatable discs engaging with the mine wall so said apron may ride over irregularities on said wall.

10. In combination with a kerf cutting mining machine, a cutting element including a cutter bar having a cutter chain movable thereabout, a conveyor beneath said cutting element, and a cuttings gathering device mounted for pivotal movement with respect

to said conveyor about a horizontal axis, said cuttings gathering device having a free end provided with a plurality of yieldable members engageable with a mine wall.

- 5 11. In combination with a kerf cutting mining machine, a cutting element including a cutter bar having a cutter chain movable thereabout, a conveyor beneath said cutting element, and a cuttings gathering device 10 mounted for pivotal movement with respect to said conveyor about a horizontal axis, said cuttings gathering device having a free end provided with a plurality of members yieldably mounted thereon for engagement with a mine wall and yieldably movable longitudinally of said cutter bar in a plane generally parallel with said cuttings gathering device.

12. In combination with a kerf cutting 20 mining machine, a cutting element including a cutter bar having a cutter chain movable thereabout, a conveyor beneath said cutting element, and a cuttings gathering device pivotally mounted on said conveyor having a free end provided with a plurality of yieldable members engageable with a mine wall.

13. In combination with a kerf cutting mining machine, a cutting element including a cutter bar having a cutter chain movable 30 thereabout, a conveyor beneath said cutting element, and a cuttings gathering device pivotally mounted on said conveyor having a free end provided with a plurality of members yieldably mounted thereon for engagement with a mine wall and for yieldable movement longitudinally of said cutter bar in a plane generally parallel with said cuttings gathering device.

14. In combination with a kerf cutting 40 mining machine, a cutting element including a cutter bar having a cutter chain movable thereabout, a conveyor beneath said cutting element, and a cuttings gathering device mounted for pivotal movement with respect 45 to said conveyor about a horizontal axis, said cuttings gathering device having a free end provided with a yieldably mounted rotatable disk engageable with a mine wall.

15. In combination with a kerf cutting mining machine, a cutting element including a cutter bar having a cutter chain movable 55 thereabout, a conveyor beneath said cutting element, and a cuttings gathering device mounted for pivotal movement with respect to said conveyor about a horizontal axis, said cuttings gathering device having a free end provided with a member yieldably mounted thereon for engagement with a mine wall and yieldably movable longitudinally of said cutter bar in a plane generally parallel with said cuttings gathering device.

16. In combination with a kerf cutting 65 mining machine, a cutting element including a cutter bar having a cutter chain movable thereabout, a conveyor beneath said cutting

element and an apron pivotally connected along the outer edge of said conveyor and having a free end adapted to engage an upright wall in an outwardly inclined position and movable along said wall to guide the cuttings upon said conveyor, said free end comprising a member yieldably mounted on said apron for engagement with a mine wall and for yieldable movement longitudinally of said cutter bar in a plane generally parallel with said apron.

17. In combination with a kerf cutting mining machine, a cutting element including a cutter bar having a cutter chain movable thereabout, a conveyor beneath said cutting element, and an apron pivotally connected along the outer edge of said conveyor and having a free end adapted to engage an upright wall in an outwardly inclined position and movable along said wall to guide the cuttings upon said conveyor, said free end comprising a yieldably mounted rotatable disc engageable with a mine wall.

18. In combination with a kerf cutting mining machine, a cutting element including a cutter bar having a cutter chain movable thereabout, a conveyor beneath said cutting element and an apron mounted for pivotal movement with respect to said conveyor about a horizontal axis having a free end adapted to engage an upright wall in an outwardly inclined position and movable along said wall to guide the cuttings upon said conveyor.

19. In combination with a kerf cutting mining machine, a cutting element including a cutter bar having a cutter chain movable thereabout, a conveyor beneath said cutting element and an apron mounted for pivotal movement with respect to said conveyor about a horizontal axis having a free end adapted to engage an upright wall in an outwardly inclined position and movable along said wall to guide the cuttings upon said conveyor, said free end being yieldable so said apron may ride over irregularities on said wall.

20. In combination with a kerf cutting mining machine, a cutting element including a cutter bar having a cutter chain movable thereabout, a conveyor beneath said cutting element and an apron mounted for pivotal movement with respect to said conveyor about a horizontal axis having a free end adapted to engage an upright wall in an outwardly inclined position and movable along said wall to guide the cuttings upon said conveyor, said free end being yieldable and comprising a plurality of yieldably mounted rotatable discs engageable with the mine wall so said apron may ride over irregularities on said wall.

Signed at Chicago, in the county of Cook and State of Illinois, this 7th day of August, A. D. 1928.

FRANK A. LINDGREN. 130
